(57) **CLAIM**

The ornamental design for a refrigerant compressor for an air conditioner of vehicle, as shown and described.

DESCRIPTION

FIG. 1 is a front view of a refrigerant compressor, according to our design.

FIG. 2 is a rear elevation view of the refrigerant compressor of FIG. 1.

FIG. 3 is a top plan view of the refrigerant compressor of FIG. 1.

FIG. 4 is a bottom plan view of the refrigerant compressor of FIG. 1.

FIG. 5 is a left side view of the refrigerant compressor of FIG. 1; and,

FIG. 6 is a right side view of the refrigerant compressor of FIG. 1.

It being understood that the broken lines are for illustrative purposes only.
